Primary Examiner — Susan E Krakower*Assistant Examiner* — Christina M. Dodson(74) *Attorney, Agent, or Firm* — Yong Chen(57) **CLAIM**

The ornamental design for a lamp stand as shown and described.

DESCRIPTION

FIG. 1 is a perspective view of a lamp stand showing my design;

FIG. 2 is second perspective view thereof;

FIG. 3 is a third perspective view thereof;

FIG. 4 is a front view thereof;

FIG. 5 is a rear view thereof;

FIG. 6 is a right view thereof;

FIG. 7 is a left view thereof;

FIG. 8 is a top view thereof; and,

FIG. 9 is a bottom view thereof.

The portions of the lamp stand shown in broken lines do not form part of the claimed design.
